DISPLAY RACK

Ann Hallabrin, Detroit, Mich.

Application July 8, 1950, Serial No. 11,021

Term of patent 14 years

(Cl. D80—9)

To all whom it may concern:

Be it known that I, Ann Hallabrin, a citizen of the United States, residing at Detroit, Michigan, have invented a new, original, and ornamental Design for Display Rack, of which the following is a specification, reference being had to the accompanying drawing, forming part thereof, wherein:

Fig. 1 is a front view of a display rack showing my new design.

Fig. 2 is a vertical sectional view of the display rack taken on the line 2—2 of Fig. 1.

Fig. 3 is a cross sectional view taken on the line 3—3 of Fig. 1.

I claim:

The ornamental design for a display rack, as shown.

ANN HALLABRIN.
